UNITED STATES PATENT OFFICE

HARRY STANLEY WOODHEAD, OF LIVERPOOL, ENGLAND, ASSIGNOR TO ASSOCIATED TELEPHONE AND TELEGRAPH COMPANY, OF CHICAGO, ILLINOIS, A CORPORATION OF DELAWARE

ELECTROMAGNETIC RELAY

Application filed September 9, 1928, Serial No. 391,149, and in Great Britain October 18, 1928.

The present invention relates to electromagnetic relays and is more particularly concerned with relays of the moving coil type which are known to possess greater sensitivity than those in which all the coils are fixed. The advantages of relays of the moving coil type, however, have hitherto been largely offset by the very much greater expense of these relays and also by the fact that they occupy a considerably greater space than relays provided with an iron armature. Both these points may be of considerable importance in certain situations, for instance in automatic telephone systems, in which a very large number of relays are required. The chief object of the present invention is to provide an improved moving coil relay which shall be comparatively inexpensive and also shall occupy the minimum of space so that a number of such relays may if desired be mounted compactly together. The attainment of these requirements is made possible owing to the fact that for the improved relay according to the invention standard parts employed for making relays as hitherto used have been utilized to a large extent.

According to one feature of the invention, in an electromagnetic relay of the moving coil type the exciting coil is supported on a core which is substantially parallel to the longer limb of an L-shaped yoke member, and is supported by said member, the operating coil being attached to a support pivoted on said yoke member.

According to another feature of the invention, in an electromagnetic relay of the moving coil type, one of the pole pieces comprises a D-shaped member secured to the yoke, while the other pole piece comprises an extension of the cylindrical core supporting the exciting coil.

A further feature of the invention is the provision of an electromagnetic relay of the moving coil type in which the movable armature of a relay of the moving iron type is used as a support for the moving coil which is arranged to be capable of substantially axial movement with respect to the core in an annular air gap about the core.

These features will be better appreciated from the following description of one method of carrying the invention into effect which should be taken in conjunction with the accompanying drawings comprising Figs. 1, 2 and 3, in which Fig. 1 is a plan view of the relay assembly, Fig. 2 is an enlarged sectional view taken along the vertical plane including the axis of the core of the assembly in Fig. 1, and Fig. 3 is a view of the D-shaped pole piece. It will be understood, however, that this description is given by way of example only and that various modifications in the constructional details could be made without exceeding the scope of the invention.

Referring now to the drawings, the relay shown comprises an exciting coil 10 mounted on a core 17 which is secured to a substantially L-shaped yoke 11 by the screw 12 or other suitable means. Secured to the end of the longer limb of the yoke 11 by a pair of screws 41, and at right-angles to it is a D-shaped polepiece 18 better seen in Fig. 3, which is drilled to accommodate the moving coil and arranged to be centralized in respect to the core 17 by means of the non-magnetic washer 14, which has an outside diameter equal to the diameter of the drilling in the polepiece 18 and which is fitted so flush with the coil check 15.

A washer 16 of magnetic material is forced over, or alternatively riveted to, the extended end of the core 17, so that it rests against the non-magnetic washer 14, and forms the other polepiece of the assembly.

The coil support 18 is pivoted at 19 on the bracket 20 which is fastened to the L-shaped yoke member 11 by a screw 21. The support 18 carries the moving coil member 22 which is composed of suitable non-magnetic material, for instance ivorine or brass, and is cup-shaped in form, is secured against the face of the support 18 by means of the screw 23, and carries the cylindrical coil in a suitable groove around its exterior. Thus the coil when in position is located in the annular space between the two pole-pieces 16 and 18 and is capable of slight movement.

In order to provide a ready means for adjustably tensioning the support 18, a light spring bracket 24 is secured thereto by means of the screws 25 and 23, and a bracket 26 is mounted on the L-shaped yoke member 11 by means of the screws 27. A helical spring 28 is supported between the two brackets 24 and 26, and coarse tensioning is effected by the adjusting screw 29, while fine adjustment may be effected by means of the controlling screw 25. The member 18 is made with an extension piece 30, which serves as a contact in the present construction and normally rests against the spring member 31, forming part of the spring assembly. The member 31 may be adjusted by a screw 32 having an insulated point and passing through a comparatively heavy bar member 33, which also forms part of the spring assembly. The contact spring with which the extension 30 engages is indicated at 34 and may be adjusted by the screw 35 which also passes through the member 33. This member is slotted and a locking screw 36 is provided to maintain the adjustments of screws 32 and 35.

The ends of the moving coil winding are connected to separate tags 37, conveniently let into the lower part of member 22, and from thence connection is made by way of the flexible leads 38, through suitable grooves in the support to the connection tags 39 of the spring assembly. This latter is secured to the yoke member 11 by means of screws 40, and the whole relay may be readily secured in position on a switch or relay frame by screws passing through suitable holes in the shorter limb of the yoke member 11.

The operation of the relay is as follows: when the exciting or core magnetizing coil 10 is energized by current flowing therethrough, a flux is set up in the magnetic circuit of the relay, which circuit includes the core 17, the heel piece or yoke 11, pole piece 13, the air gap around pole piece 16 and that pole piece. Since the cup 22 carrying the operating coil is made of non-magnetic material, the flux created by the energization of coil 10 will have no effect on the cup and consequently the armature of the relay. However, when the operating coil is energized, it makes that coil magnetic and the coil, since it is free to move, moves into the air gap where the magnetic lines of force are concentrated. This movement, which may be said to be substantially axial with respect to the core, causes the armature arm 30 to move and thereby close contact between spring 31 and contact spring 34.

It will be appreciated therefore that according to the invention a very compact and inexpensive moving coil relay has been devised, these properties permitting the use of the relay in a number of situations in

automatic telephone circuits where its greater sensitivity will be advantageous.

I claim:

1. In an electromagnetic relay, a magnetizable core, a magnetizing winding on said core, a yoke member lying parallel to said core and on only one side thereof, a D-shaped pole piece secured to one end of said yoke member and surrounding one end of said core to form an air gap around the end of the core, an armature pivoted on said yoke member, a movable coil secured to said armature and projecting into said air gap, the energization of said movable coil while said magnetizing winding is energized, moving said armature on its pivot. 70 75 80

2. In an electromagnetic relay, a magnetizable core, a magnetizing winding thereon, a cylindrical pole piece forced onto one end of said core, a yoke member lying parallel to said core and on only one side thereof, a D-shaped pole piece having a circular aperture therein and secured to one end of said yoke member in position to surround said cylindrical pole piece with an air gap therebetween, a circular washer on said core and of such size as to fit in the circular aperture to hold said D-shaped pole piece concentric with said cylindrical pole piece, an armature pivoted on said yoke member and provided with a spring-moving arm, a cup-shaped member secured to said armature and projecting into said air gap, an operating winding on said cup-shaped member and adapted, when energized while said magnetizing winding is energized, to move said armature and arm, and contact springs mounted on said yoke member in position to be moved by said arm. 90 95 100

In testimony whereof I hereunto affix my signature this 21st day of August, 1929. 105

HARRY STANLEY WOODHEAD.
